UNITED STATES PATENT OFFICE.

EDWIN S. ROBERTS, OF GOUVERNEUR, NEW YORK, ASSIGNOR TO INTERNATIONAL LACE COMPANY, OF GOUVERNEUR, NEW YORK, A CORPORATION OF NEW YORK.

LACE FABRIC.

1,126,868.

Specification of Letters Patent.

Patented Feb. 2, 1915.

Application filed February 18, 1914. Serial No. 819,335.

To all whom it may concern:

Be it known that I, EDWIN S. ROBERTS, a citizen of the United States, and a resident of Gouverneur, in the county of St. Lawrence and State of New York, have invented certain new and useful Improvements in Lace Fabric, of which the following is a specification.

My invention relates to lace fabric, such as may be made on a lace curtain machine.

The object of my invention is to so construct the fabric that it will be substantial and durable and so that it will be of novel appearance.

Another object is to produce a lace fabric of this character which will be no more expensive to make than other fabrics of a corresponding grade; and to produce a fabric which may be made upon machines which are now in general use for making lace curtains.

Under my present invention lace fabrics may be made having solid or filled portions of rectangular shape and with openings of rectangular shape, all arranged to produce a very pleasing effect; and the fabric may be of substantial construction. Fabrics may be made according to my invention, suitable for lace curtains, or they may be made of heavier threads and be suitable for draperies, portières and such like.

The principle of my invention resides in making a lace fabric having the warp threads spaced different distances apart and in having some of the spool threads arranged as usual and others combined in such manner that they follow along together in the design and are tied to the same warps.

In the drawings forming part of this application, Figure 1 is an elevation of a portion of lace fabric constructed in accordance with my invention, as it ordinarily appears to the observer. Fig. 2 is a similar view of one side of the fabric, made on an enlarged scale to show the construction, Fig. 3 is a similar view of the reverse side of the fabric, and Fig. 4 is an enlarged detail showing the fabric as viewed from the same side as in Fig. 3.

The ground work or foundation of the fabric consists, as in other lace fabrics, of the warp threads, though these are here arranged in a novel way. These warp threads may be said to be of different gages or to be arranged at different distances apart. Sev-

eral of these warp threads are arranged the same, or substantially the same, distance apart, while others are arranged different or greater distances apart. There may be what might be called a series of groups of warp threads, each group being spaced a greater distance from the adjacent groups than the distance between the individual warps of a group. In constructing the lace for instance on a six point machine, the warps may be threaded through the warp bar in this manner; three warps threaded through their respective apertures in the bar and the next warp omitted, then three threaded and one omitted, etc. Where a warp is omitted there will naturally be formed a wider space between the adjacent warps. This is stated merely as an example, as the particular numbers and arrangement may be more or less varied without departing from the structural character of the fabric. If the usual lace curtain machine is employed in making the fabric, a certain number of the warps may be omitted in the above manner, and the corresponding bobbins and carriages removed.

In the drawings I have shown the warp threads running vertically. The warp threads 1, 2 and 3 for instance, are shown spaced equally apart, or of the same gage. In the next position the warp is omitted; and then the threads 1, 2, 3 are repeated; so that the distances between the threads 1, 2, and 2, 3, are alike, but the distance between the threads 3, 1, is greater than the distance between any two of the threads 1, 2, or 2, 3.

For each warp thread there is a bobbin thread for tying the spool threads to the warps; and, since the warps are arranged different distances apart, so the bobbin threads will be arranged to correspond. The bobbin threads 4, 5, 6, are arranged to tie on the warps 1, 2, 3, respectively, and they are, therefore, approximately the same distance from each other; but the distance between 6 and 4 is greater than the distance between 4 and 5, or 5 and 6. In order to obtain this arrangement I prefer to omit a certain number of bobbins and carriages by removing them from the machine. For instance, in the making of the fabric here illustrated I arrange the three bobbins carrying the threads 4, 5, 6, in the usual manner, these corresponding with the warps 1, 2, 3. The next or fourth bobbin is omitted or re-

moved from the machine; and this arrangement is repeated throughout the machine. The spool threads are retained to their full number. That is, there are as many 5 spool threads as there ordinarily would be in customary practice, but they are differently arranged. If for instance, the warps are arranged three in and one out, this omission is not followed as to the spool threads, but 10 there will be as many of these as the ordinary gage of the work calls for. That is, if the warps 1, 2, 3, are arranged to correspond with a six point arrangement then there will be, say, six spool threads to the inch; but 15 they will not be equally spaced in the construction. In the making of the fabric here shown I arrange three spool threads in the usual manner, threading them through the usual apertures in the guides on the spool bar. In the next position the spool thread is not threaded in the usual manner, but it is 20 carried over and threaded through the same guide as the adjacent thread.

In the fabric here shown the warps 1, 2, 3, 25 are equally spaced and the warps 3, 1 are spaced a greater distance apart. The spool thread 7 passes back and forth between the warps 1 and 3, crossing the intermediate warp 2; and it is tied to the warps 1, 3, by 30 the bobbin threads 4, 6, respectively. The spool thread 8 passes back and forth between the warps 1 and 2 and is tied to them by the bobbin threads 4, 5, respectively; and this construction preferably continues down 35 the full length of the material, forming a sort of bar appearance. This arrangement is true of all the several spool threads 7 and 8 throughout the width of the fabric. The spool threads 9, 10 follow together and they 40 pass back and forth between the warps 1, 3, and are tied to them by the bobbin threads 4, 6, respectively. The spool threads, in this arrangement, are double; or in multiple 45 across the wider spaces formed between the more distantly spaced warps, so that this space is filled sufficiently to produce the desired appearance and strength. This arrangement is continued down the fabric for the desired distance; and then a change occurs. At any point, say at 11, the spool 50 threads 9, 10, still following together, are pillared down the warp 1 and are tied by the bobbin thread 4. At any lower point, say at 12, the previous construction is repeated; 55 that is, the spool threads 9, 10, are again carried back and forth between the warps 1, 3, and are tied by the bobbin threads 4, 6.

By means of the above construction it is possible to produce an article of novel appearance and of substantial construction. 60 Both the upright and cross bars of the de-

sign are substantial and permanent. The fabric consists of rectangular filled portions inclosing rectangular openings which will properly retain their shape.

65

Having described my invention, what I claim is:

1. A lace fabric comprising a plurality of warp threads, a plurality of bobbin threads and a plurality of spool threads, said warp threads being arranged in different gages, a plurality of said spool threads passing, together, back and forth between the warps of wider gage, thence pillared down one of said warps and again passing back and forth, together, between said warps of wider gage, said spool threads being tied to the warps by said bobbin threads.

2. A lace fabric comprising a group of warp threads, arranged in the same gage, another group of warp threads arranged in the same gage as the first group, the said groups being arranged in a gage of greater width than the gage of the individual warps of the groups, spool threads providing a filling between the warps of each group and a plurality of spool threads following together, and passing back and forth between adjacent warps of the respective groups, and thence pillared down one of said warps and again passing back and forth between said adjacent warps, to form an interrupted filling, and bobbin threads tying said spool threads to the warp threads.

3. A lace fabric comprising groups of warp threads having the several groups arranged in the same gage, and having the groups arranged in a relatively wider gage than the individual warps of the groups, a filling for the warps of each group, comprising spool threads looped back and forth, respectively between adjacent and remote warps of a group to form a continuous filling between said warps, bobbin threads tying said spool threads to said warps, and a plurality of spool threads following together and looped across between adjacent warps of the different groups, and being thence pillared along one of said warps and again looped across between said adjacent warps of different groups, to form an interrupted filling between different groups of warps and bobbin threads tying the said last mentioned spool threads to the warps.

Signed at Gouverneur, in the county of St. Lawrence, State of New York, this 12th day of February, 1914.
